UNITED STATES PATENT OFFICE.

RICHARD KITSON, OF LOWELL, MASSACHUSETTS, ASSIGNOR TO THE KITSON MACHINE COMPANY, OF SAME PLACE.

COTTON OPENER AND LAPPER.

SPECIFICATION forming part of Letters Patent No. 272,709, dated February 20, 1883.

Application filed January 19, 1882. (No model.)

To all whom it may concern:

Be it known that I, RICHARD KITSON, of the city of Lowell, county of Middlesex, and State of Massachusetts, have invented a new 5 and useful Improvement in Cotton Openers and Lappers, of which the following is a specification.

My improvement relates to machines for opening cotton and forming a lap therefrom; 10 and its object is to provide a machine which will produce a lap having a perfectly true, square, and straight edge, and one having the same solidity near the edge that it has in any other part. I accomplish this object by the 15 mechanism illustrated in the accompanying drawings, in which—

Figure 1 is a longitudinal vertical section through my machine. Fig. 2 is an elevation of the calender-rolls seen in Fig. 1 removed 20 from the machine. Fig. 3 is a section of the rolls seen in Fig. 2.

A is the apron, on which the cotton is placed to be fed to the machine.

a a are feed-rolls, by which the cotton is 25 grasped and held while operated upon by the beater B.

C C are screens or cages, on which the fibers of cotton are deposited when thrown forward by the beater with the current of air created by 30 it. These screens are connected with the exhaust-fan F, which creates a partial vacuum in the screens by exhausting the air from them, so that the fibers of cotton thrown forward by the beater will be felted upon the screens or 35 cages, from which they are taken by the draw-off rolls e, when they pass to the calender-rolls D, the upper and larger one, d, of which is made of a length to conform exactly to the desired width of the lap. The lower one, e, is provided with collars g, which extend up past the 40 ends of the upper roll, so that it moves freely but closely between them. The sheets of cotton to form the lap are passed between these calender-rolls, by which they are pressed together 45 to be united to form a lap, and as there is no space between the rolls, except a space the exact width of the lap to be made, the two sheets will be compressed from edge to edge

equally, and will be delivered with a perfectly square edge which is perfectly straight.

Heretofore the calender-rolls have been made straight without collars, and the width of the lap has been controlled by guide pieces or cheeks, which were placed in advance of the rolls; but as these guides could not 50 pass between the rolls at the point where the pressure came, the edges widened out irregularly, because of the pressure and the lack of support in one direction at the place where the pressure was applied, so that the lap was 55 made irregular, and the two sheets of cotton forming the lap were not so perfectly compressed together at the edges as near the more central parts, and the lap therefore was very liable to begin to split at its edges when fed 60 to the card. As there has heretofore been no way of compressing two sheets as firmly together near their edges as in their central parts, because of the sidewise escape of the fibers at the edges, it has not been found 65 practical to produce a lap on a two-screen machine which would not split. This would especially be liable to happen when the edge of one sheet overreached the edge of the other 70 at any part.

With my present device all raggedness or irregularity of the edge of the lap is avoided, and the lap has a straight edge and square corners, and the fibers are equally compressed in all parts of the lap, so that when two 80 cages are used the two sheets formed by them are pressed together and united equally well from one edge to the other, and the possibility of a split, resulting from a separation beginning where a defective union of the edges exists, which, being begun, extends back into the lap where the sheets are most firmly united, no longer exists. I do not, however, intend 85 to confine the use of my improved calender-rolls to machines having two cages, but expect to use it with a single screen to make a 90 square-edged lap.

In the mechanism shown in the drawings the direction of movement of the different parts is indicated by arrows, the parts being 95 driven by belts operating on pulleys driven

from conveniently-placed counter-shafts, and the feed and calender rolls are geared together, all in the usual well-known manner of driving cotton openers and lappers, and the gear and pulleys are not therefore shown.

5 What I claim as new and of my invention is—

The combination of the beater B and cages

C with the calender rolls D, one of which is provided with collars which extend past the 10 end of the other, substantially as described.

RICHARD KITSON.
